SLED

Glenn G. Stoddard, Oak Creek, Wis., assignor to Toledo Guild Products, Inc., Toledo, Ohio, a corporation of Ohio

Filed Dec. 6, 1965, Ser. No. 98

Term of patent 14 years

(Cl. D34—15)

FIG. 1 is a perspective view showing a sled embodying my new design;

FIG. 2 is a top view of the sled shown in FIG. 1;

FIG. 3 is a front end view of the sled shown in FIG. 1;

FIG. 4 is a side view of the sled shown in FIG. 1; and

FIG. 5 is a rear end view of the sled shown in FIG. 1.

I claim:

The ornamental design for a sled, as shown.
